(57) **CLAIM**

The ornamental design for a flat sided thermal container, as shown and described.

DESCRIPTION

FIG. 1 is a front elevational view of the flat sided thermal container of the present invention;

FIG. 2 is a rear elevational view of the flat sided thermal container of FIG. 1;

FIG. 3 is a left side elevational view of the flat sided thermal container of FIG. 1, the right view being a mirror image thereof;

FIG. 4 is a top plan view of the flat sided thermal container of FIG. 1;

FIG. 5 is a bottom plan view of the flat sided thermal container of FIG. 1; and,

FIG. 6 is a top, front, left side perspective view of the flat sided thermal container of FIG. 1.

The broken lines showing of lettering in FIGS. 3 and 6 are for illustrative purposes only and form no part of the claimed design.
